UNITED STATES PATENT OFFICE.

DAVID S. PAISLEY, OF CLEVELAND, OHIO.

BOTTLE-STOPPER.

SPECIFICATION forming part of Letters Patent No. 233,796, dated October 26, 1880.

Application filed March 30, 1880. (Model.)

To all whom it may concern:

Be it known that I, DAVID S. PAISLEY, of Cleveland, in the county of Cuyahoga and State of Ohio, have invented a new and useful

5 Improvement in Bottle-Stoppers; and I do hereby declare that the following is a full and exact description of the same, reference being had to the accompanying drawings, and to the letters of reference marked thereon.

10 My invention has reference to certain improvements in corks or stoppers for bottles, and is particularly designed to afford a stopper which will fit a variety of bottles of different shape and size, and can be used many 15 times without destruction. It is adapted to any liquid except the stronger acids without being affected thereby, is no larger than an ordinary cork, and very simple in its construction.

20 In the drawings, Figure 1 is a perspective of my bottle-stopper, showing it inserted in the neck of an ordinary wine-bottle. Fig. 2 is a sectional view of the stopper, and Fig. 3 another form of disk which I employ at the top.

25 B is a wing-nut, threaded to fit the bolt C, and bearing upon the disk D, which is provided with a projecting lip, a, to be held by the thumb of the left hand when turning the nut to fasten the stopper in the neck of the bot-

30 tle A.

E is a cylinder, of wood or other suitable

material; and F, another cylinder, of the same material, or simply a metallic washer.

G is a ring or cushion, of rubber, as a piece of rubber tubing.

35 When the stopper is placed in a bottle, by turning the nut B the rubber G is compressed and expanded outwardly against the inner neck of the bottle in the form shown by the dotted lines G', the disk being drawn upward 40 and compressing the rubber, as shown at F' in Fig. 2, thus effectually closing the bottle and preventing the escape of the stopper.

45 When desired, the stopper can be removed by a reverse movement of the nut.

Instead of the lip a, I can use a fluted or corrugated disk, as shown in Fig. 3.

Having thus fully described my invention, what I claim as new, and desire to secure by Letters Patent, is—

50 As a new and useful article of manufacture, the bottle-stopper described, consisting of bolt C, cylinder F, rubber ring G, cylinder E, wing-nut B, and disk D, with lip a, all constructed and arranged to operate substantially as set 55 forth and shown.

This specification signed and witnessed this 18th day of March, 1880.

DAVID S. PAISLEY.
